(57) **CLAIM**

The ornamental design for a hair dryer, as shown and described.

DESCRIPTION

FIG. 1 is a front, right and top perspective view of a hair dryer, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of a portion of the hair dryer shown within the area designated as 9 in FIG. 1.

FIG. 10 is an enlarged view of a portion of the hair dryer shown within the area designated as 10 in FIG. 1; and, FIG. 11 is an enlarged view of a portion of the hair dryer shown within the area designated as 11 in FIG. 2.

The broken lines depict portions of the hair dryer that form no part of the claimed design.

The dot-dash broken lines in FIGS. 1, 2 and 9-11 depict the boundaries of the enlargements that form no part of the claimed design.

1 Claim, 11 Drawing Sheets
